DESIGN FOR AN UMBRELLA STAND

Morris Katcher, New York, N. Y.

Application August 10, 1939, Serial No. 86,574

Term of patent 7 years

To all whom it may concern:

Be it known that I, Morris Katcher, a citizen of the United States, residing at New York, in the county of Queens and State of New York, have invented a new, original, and ornamental Design for an Umbrella Stand, of which the following is a specification, reference being had to the accompanying drawing, forming part thereof.

Fig. 1 is a perspective view of an umbrella stand, showing my new design, and

I claim:

The ornamental design for an umbrella stand, as shown.

MORRIS KATCHER.
